UNITED STATES PATENT OFFICE.

OTTO JAEGER, OF ELKINS PARK, PENNSYLVANIA, ASSIGNOR TO HARRY S. KELSEY, OF BOSTON, MASSACHUSETTS.

DISPENSING DEVICE.

1,302,052.

Specification of Letters Patent. Patented Apr. 29, 1919.

Application filed August 22, 1917. Serial No. 187,527.

To all whom it may concern:

Be it known that I, OTTO JAEGER, a citizen of the United States, residing at Elkins Park, in the county of Montgomery, State of Pennsylvania, have invented a certain new and useful Improvement in Dispensing Devices, of which the following is a specification, reference being had to the accompanying drawings, forming a part thereof.

10 My invention relates to improvements in dispensing apparatus having a compartment for the articles to be dispensed and having an outlet opening for the said articles and a door controlling the outlet opening.

15 The object of my invention is to provide a novel simple and efficient means for moving the articles to be dispensed toward or through the outlet opening of the compartment, when the machine is operated, to a position from which they may be conveniently removed by hand.

20 With this and related objects in view, the invention consists in the novel construction and combinations of parts hereinafter fully described and claimed.

25 In the accompanying drawings illustrating my invention:

Figure 1 is a vertical section, on line 1—1 of Fig. 3, through a dispensing apparatus embodying my invention and showing the door for controlling the outlet opening of the compartment in the closed position, and the support for the articles to be dispensed in the inner position.

30 Fig. 2 is a view similar to Fig. 1, showing the door in the open position and the article support in the outer position.

Fig. 3 is a horizontal section of the apparatus, on line 3—3 of Fig. 1.

40 Fig. 4 is a vertical section of the apparatus, on line 4—4 of Fig. 1.

Figs. 5 and 6 are vertical sections of the apparatus on line 5—5 of Fig. 4, showing the parts in positions corresponding with 45 the positions shown in Figs. 1 and 2, respectively.

50 Referring to the drawings, 6 designates a frame or casing which may be of any suitable shape and size for its intended purpose. The casing 6 incloses a compartment 7 for the articles to be dispensed. The compartment 7 has an outlet opening 8 in the front wall thereof through which the articles may be removed from the compartment, 55 and it has an inlet opening 9 in the rear wall

thereof through which the articles may be introduced to the compartment.

The inlet opening 9 is normally closed by a door 10 hinged at its upper edge to the casing 6; and the outlet opening 8 is normally closed by a door 11 carried by a pair of arms or brackets 12 projecting fixedly from a shaft 13 which is mounted to turn in walls 14 and 15 of the casing 6. The door 11 is thus pivoted to the casing 6 by means of the shaft 13, and the door 11 is curved on lines struck from the axis of the shaft 13, whereby, when the shaft 13 is turned back and forth, the door 11 will be moved from its normal or closed position, shown in Fig. 1, to its open position, shown in Fig. 2, and back again. When the door 11 is moved to its open position, it engages the door 10 and moves it outwardly to the position shown in Fig. 2, for a purpose hereinafter explained.

One end of the shaft 13 extends outwardly beyond the wall 14 and has a toothed sector 16 secured thereon. The teeth of the sector 16 are in mesh with the teeth of a rack 17 which is secured to a weight 18. The weight 18 is in the form of an oblong bar and it is vertically slideable against the face of the wall 14 and is held in place and guided by screws 19 which extend through vertical slots 20 in the weight 18 and which are screwed into the wall 14. When the weight 18 is raised to the position shown in Fig. 5 it is adapted to be held therein by an arm 20 which is pivoted, at 21, on the wall 14, and the free end of which engages a notch 22 in the weight. When the arm 20 is moved outwardly to clear the notch 22, the weight 18 will descend by gravity to the position shown in Fig. 6, and when the weight 18 is returned to the position shown in Fig. 5, the arm 20, resting against the side of the weight 18, will automatically reengage itself with the notch 22 to hold the weight in the elevated position.

100 The door 11, sector 16 and weight 18 are so relatively arranged that when the weight is raised from the position shown in Fig. 6 to the position shown in Fig. 5, the door 11 will be moved from the open to the closed position; and that when the arm 20 is operated to release the weight 18 it will descend by gravity and move the door 11 from the closed to the open position.

105 Within the compartment 7 and forming 110

the floor thereof is a horizontal plate 23 which is adapted to receive and support the articles to be dispensed. The lateral edge portions of this plate 23 are slidably fitted 5 within grooves formed in the inner sides of horizontally-disposed, parallel bars 24 which are secured to the opposing inner faces of the walls 14 and 15 of the casing 6. The bars 24 have openings 25 formed therein 10 through which the door carrying arms 12 extend, as clearly shown in Fig. 3.

The plate 23 is slidable from its inner or normal position, shown in Fig. 1, out through the outlet opening 8 of the compartment 7, to its outer position, shown in Fig. 2, and back again to its normal position; and the devices for thus moving plate 23 are as follows:

Secured to the bottom of the plate 23, 20 near the respective sides thereof, are rack bars 26 having teeth which mesh with the teeth of two pinions 27 on a shaft 28 which extends parallel to the shaft 13 and between the casing walls 14 and 15 and is adapted to 25 turn therein. The teeth of the pinions 27 are also in mesh with the teeth of the two sectors 29 which are secured on the shaft 13, whereby, when the shaft 13 is turned by the lowering of the weight 18 to the position 30 shown in Fig. 6, the supporting plate 23 will be projected out through the compartment outlet opening 8 from the position shown in Fig. 1 to the position shown in Fig. 2; and, when the weight 18 is raised to 35 the position shown in Fig. 5, the plate 23 will be returned to its normal position shown in Fig. 1.

The invention is especially adapted for use in connection with vending machines, 40 and particularly with vending machines of the class used in restaurants or lunch rooms known as "automats", and the operation thereof, briefly described, is as follows:

The frame or casing 6 is adapted to form 45 part of the partition wall which separates the customers from the attendant of the apparatus, the door 11 opening on the side of the customers and the door 10 opening on the side of the attendant.

50 The attendant opens the door 10 and places the article or articles to be sold or dispensed within the compartment 7 and upon the plate or support 23. In the drawings, I have shown a china plate 30 on the supporting plate 23, the china plate 30 being adapted to contain any article of food such as a piece of pie or cake and to be placed within the compartment 7 by the attendant. I have shown an upwardly extending stop 55 or bracket 31 secured on the rearward portion of the supporting plate 23 and against which the china plate 30 may be placed to properly center the china plate upon the supporting plate 23.

60 65 The article thus placed within the com-

partment 7 is delivered to the customer purchasing the same by moving the arm 20 to release the weight 18. The arm 20 may be thus moved by hand by the attendant or it may be moved by suitable coin-controlled mechanism operated by the customer inserting the proper coin or coins into the same. When the weight 18 is released it descends by gravity to the position shown in Fig. 6, thereby raising or opening the delivery door 11, and, at the same time moving the supporting plate 23, with the china plate 30 and article of food thereon, out through the outlet opening 8, the parts coming to rest in the position shown in Fig. 80 2, with the plate 30 projected into a position to be conveniently removed from its support 23 by the customer.

When the door 11 is moved to the open position, as just described, it moves the door 10 out to the position shown in Fig. 2, thereby indicating to the attendant that the compartment 7 is empty. The attendant then raises the weight 18 and reengages the arm 20 with the notch 22 to hold the weight elevated, thereby moving the supporting plate 23 back to the inner position and closing the door 11 and leaving the parts in the position shown in Fig. 1. This being done, the attendant opens the door 10 and places a fresh 95 article to be dispensed upon the supporting plate 23 within the compartment 7 for a succeeding dispensing operation.

I claim:

1. In a dispensing apparatus, a casing 100 providing a compartment having oppositely disposed outlet and inlet openings, a pair of parallel grooved guiding bars at the base of the compartment, a plate supported between said grooved guide bars and adapted to be slidably reciprocated therein to and from said outlet opening, a pair of rack bars on the under face of said plate, a transversely disposed rotatable shaft, with connecting actuating devices between said shaft and said rack bars, a pivotally mounted door, means to support and move the door to open and close said outlet opening, connecting actuating devices between said door-supporting means and said shaft, gravity-actuated means normally inoperative, with means to release the same, to actuate said rotatable shaft, whereby coördinated motion is imparted to said plate-actuating means and door-operating means, in both directions.

2. A dispensing apparatus comprising a casing providing a compartment having an outlet opening, a horizontally disposed plate 125 slidable to and from said outlet opening, guiding devices for said plate, a pair of rack bars on the under face of said plate, a rotatable shaft extending transversely beneath said plate and mounted to turn in the casing, connecting actuating means between 130

- 5 said rack bars and said shaft, a pivotally mounted door normally closing said outlet opening, a bracket adapted to support said door and having a hub end fixedly mounted on said shaft, means to normally hold said shaft against operative rotation, and manually actuated devices to release said holding means and actuate said shaft; said elements being combined and coördinated whereby 10 when said shaft is rotated to impart a rearward movement to the door to uncover said outlet opening said supporting plate will be moved in the opposite direction in unison therewith.
- 15 3. In a dispensing apparatus, a casing providing a compartment for the articles to be dispensed, said casing having an outlet opening, a horizontally disposed supporting plate for said articles, slideable to and from 20 said outlet opening, within the compartment, a shaft mounted to turn in the casing, a rack bar secured to the under face of said slideable plate and operated by said shaft when turned to move said plate to and from said opening, connecting actuating devices between said rack bar and shaft, a door normally closing said opening, supporting means for said door connected to and carried by said shaft, a weight, means to maintain said weight normally elevated and operative to release the same, and connecting actuating devices between said weight and said shaft, whereby when said weight is released said shaft will be turned to slide said supporting plate and to actuate said door. 25 30 35

In testimony whereof, I have hereunto affixed my signature this 21st day of August, 1917.

OTTO JAEGER.
